PATENTED
JUN 1 1869

United States Patent Office.

HENRY BRIDE SCHOLES, OF NEW YORK, N. Y.

Design No. 3,529, dated June 1, 1869.

DESIGN FOR A LAMP-POST.

The Schedule referred to in these Letters Patent and making part of the same.

To all whom it may concern:

Be it known that I, HENRY BRIDE SCHOLES, of the city of New York, in the county and State of New York, have designed a new Design for an Ornamental Cast-Iron or other Metal Street-Lamp Post, of which a full, clear, and exact description is shown by the accompanying drawing, which forms a part of this specification.

Upon the drawing—

Figure 1 represents an upright side view of said lamp-post.

What I claim as my invention, and desire to secure by Letters Patent, is—

The design for the manufacture of ornamental street-lamp posts, to be made of cast-iron or other metal, as herein set forth.

H. B. SCHOLES.
